CIRCULAR LOOM

Frank Corbyn Hale and James Russell Yorke,
Spondon, near Derby, England, assignors to
Celanese Corporation of America, a corpora-
tion of Delaware

Application November 12, 1936, Serial No. 110,428
In Great Britain December 23, 1935

6 Claims. (Cl. 139—13)

The present invention relates to circular looms, i. e., looms in which the warp threads are arranged in a circle and in which the weft is laid by means of a relative circular motion between 5 the shuttle or shuttles and the warp threads.

Such relative circular motion between the shuttle or shuttles and the warps, together with the substantial concealment of the shuttle or shuttles within the warp shed or sheds, renders difficult the detection of broken weft threads and the necessarily immediate communication of such breakage from the shuttle to means which serve to stop the weaving operation.

It is, of course, of the utmost importance to 15 stop the loom immediately upon weft breakage, and especially so in multi-shuttle looms, where if the loom continues weaving with one weft absent, a flaw results that cannot be rectified. Thus, even if stoppage is effected so quickly that 20 only one weft from another shuttle has been laid in the portion of the fabric where the breakage of weft has occurred, it may not be possible to "unweave" that weft—especially as any "unweaving" might probably have to extend to the wefts 25 laid by the other shuttles in the rest of the fabric periphery.

According to the invention, weft breakage is 30 detected by a member carried by the shuttle and disposed in the path of the weft thread between thread tensioning means and the fell of the fabric. Release of the detector member upon breakage of the weft causes a member under control 35 of the detector member to be propelled through one warp sheet to bring about the operation of means disposed outside the warp shed for bringing weaving to an end. These last-mentioned 40 means can be arranged to operate with great rapidity, e. g., by operating electrically as described in U. S. Patent No. 2,027,459 so that weaving can cease in time for the fault caused by the 45 weft breakage to be remedied. The invention has the advantage, moreover, that the stop mechanism is not influenced by slackness of the thread delivered from the supply, the thread-tensioning 50 means not only delivering the weft at the required weaving tension, but also guarding against the release of the detector member by slackly wound weft or slackness resulting from slight overrunning of a rotatable weft spool or an arm 55 serving to unwind weft from a stationary spool when the loom stops.

At the commencement of the weaving operation the thread tensioning means is adjusted in accordance with the weaving tension desired in 55 the weft, and the pressure of the detector mem-

ber against the weft thread is adjusted in accordance with such tension. Thus, while the detector member is still capable of operating on weft breakage, mere slackness in the weft proceeding from the supply is insufficient to bring 5 about the operation of the detector member.

By way of example a form of apparatus according to the invention will now be described in greater detail with reference to the accompanying drawing of which

Fig. 1 is a front elevation of the apparatus incorporated in a shuttle;

Fig. 2 is a front elevation of part of Fig. 1, on larger scale; and

Fig. 3 is a plan of part of Fig. 1.

Referring to Fig. 1 the shuttle 4 is of the type described in U. S. Patent No. 2,050,328 and is supported and positioned in the loom by rotatable vane wheels 5 which are mounted on a shaft 6 and engage pairs of flanged rollers 7 carried by 20 the shuttle.

Weft thread 8 proceeds from a supply spool 9 to a guide 10 from which the thread passes through a guide 11, held in an aperture formed in a plate 12, to the fell 13 of the fabric. Disposed on the plate 12 in a position to engage the thread 8 as it passes from the spool 9 to the guide 10 is a device for tensioning the thread. The device comprises a pair of smooth discs 14 mounted on a central stud 15 and urged into 25 contact with each other by a compression spring 16, the pressure of which is adjustably controlled by a nut 17 which screws on the stud 15.

Between the tensioning device 14 and the guide 10 is a detector member formed as a two-armed 35 lever 18, 19 pivoted at 20 (Fig. 2) to an upstanding portion of the plate 12 and urged into clockwise rotation about the pivot by a spring 16 (Fig. 3). The arm 18 carries a thread guide 21 which bears down on the tensioned thread 8, 40 the thread normally preventing the lever from rotating about its pivot. When the detector member is in the normal (thread-engaging) position the arm 19 bears against an arm 22 of a bell-crank lever comprising arms 22, 23 pivoted 45 at 24 to the plate 12. A flat coil spring 25 associated with the bell-crank lever tends to rotate the lever in an anti-clockwise direction, such motion being restrained by the arm 19 of the detector member.

As will be apparent from the drawing slackening of the thread 8 between the spool 9 and the tensioning device 14 has no effect on the tension in that part of the thread 8 extending from the tensioning means 14 to the fell 13 of 55

the fabric and consequently cannot bring about the operation of the detector member 18, 19 and the bell-crank lever 22, 23.

On breakage of the weft thread 8, however, restraint is removed from the guide 21 of the detector member with the result that the member rotates clockwise about its pivot 20 under the influence of the spring 181 and frees the bell-crank lever 22, 23. The bell-crank lever immediately rotates anti-clockwise about its pivot 24 under the influence of the spring 25 with the result that the arm 23 of the lever is urged beyond the width of the plate 12 and through a sheet of the relatively moving warp threads (a few of which are illustrated diagrammatically at 27 in Fig. 3) which push the arm 23 and tend to continue the anti-clockwise rotation of the bell-crank lever.

This movement of the arm 23 brings it into contact with a pin 28 outstanding from a rod 29 which is longitudinally disposed on the plate 12 with the result that the rod is propelled rearwardly through the warp sheet 27 and contacts with a feeler 30 (Fig. 3). The feeler 30 actuates an electric switch 31 of the type described in U. S. application S. No. 98,274 filed 28th August, 1936 and which operates means for bringing weaving to an end. For full details of the means for bringing weaving to an end reference may be had to U. S. Patent No. 2,027,459. In Fig. 1 the rod 29 is shown broken off short of the tensioning device 14 for convenience of illustration of the tensioning device and the detector member 18, 19. The end of the rod is shown in full however in Figs. 2 and 3.

The arms 22, 23 of the bell-crank lever are capable of independent rotation about the pivot 24 and are normally maintained in the angular relation shown in Fig. 3 by a flat coil spring 32 an end of which is secured to each arm of the lever. In this manner the arm 22 of the lever normally engaged by the arm 19 of the detector member need only rotate sufficiently on release of the detector member to bring the arm 23 into contact with the relatively moving warp threads 27 which then continue the rotation of the arm 23 independently of the arm 22.

When the arm 23 is released from the warp threads 27 on repair of the breakage in the weft thread 8 the spring 32 connecting the two arms of the bell-crank lever returns the arm 23 automatically to the normal position (viz. as shown in Fig. 2) in readiness for the resetting of the lever and the detector member.

Having described our invention what we desire to secure by Letters Patent is:—

1. In a circular loom, a shuttle for laying weft thread at the fell of the fabric, thread tensioning means disposed in the path of the thread at a point between the supply and the fell of the fabric and adapted to impart tension to that length of the thread which extends from the tensioning means to the fell of the fabric, a movable detector member carried by the shuttle and adapted to be restrained from movement by the tensioned length of thread and to be freed for movement on breakage of such thread, the tension imparted to the thread by the tensioning means restraining the detector member irrespective of the state of the tension in the thread extending from the supply to the tensioning means, and movable means controlled by the detector member and adapted on freeing of the detector member to be propelled through a warp sheet to bring about the operation of means disposed at the other side of the warp sheet for bringing weaving to an end.

2. In a circular loom, a shuttle, a spool in said shuttle for supplying weft to be laid at the fell of the fabric, thread tensioning means disposed on the shuttle in the path of the thread at a point between the supply and the fell of the fabric and adapted to impart tension to that length of the thread which extends from the tensioning means to the fell of the fabric, a pivoted detector member carried by the shuttle and adapted to be restrained from rotating about its pivot by the tensioned length of thread, and to be freed for movement on breakage of such thread, the tension imparted to the thread by the tensioning means restraining the detector member irrespective of the state of the tension in the thread extending from the supply to the tensioning means, and a pivoted member controlled by the detector member and adapted on freeing of the detector member to rotate about its pivot so as to propel an extension of the member through a warp sheet to bring about the operation of means disposed at the other side of the warp sheet for bringing weaving to an end.

3. In a circular loom, a shuttle for laying weft thread at the fell of the fabric, thread tensioning means disposed in the path of the thread at a point between the supply and the fell of the fabric and adapted to impart tension to that length of the thread which extends from the tensioning means to the fell of the fabric, means for adjusting the degree of tension imparted to the thread by the tensioning means, a movable detector member carried by the shuttle and adapted to be restrained from movement by the tensioned length of thread and to be freed for movement on breakage of such thread, the tension imparted to the thread by the tensioning means restraining the detector member irrespective of the state of the tension in the thread extending from the supply to the tensioning means, and movable means controlled by the detector member and adapted on freeing of the detector member to be propelled through a warp sheet to bring about the operation of means disposed at the other side of the warp sheet for bringing weaving to an end.

4. In a circular loom, a shuttle, a spool in said shuttle for supplying weft to be laid at the fell of the fabric, thread tensioning means disposed on the shuttle in the path of the thread at a point removed from the fell of the fabric, a pivoted detector member carried by the shuttle, a spring adapted to urge said detector member to rotate about its pivot, the detector member being restrained from moving by the tensioned thread extending between the tensioning means and the fell of the fabric and freed for movement on thread breakage, and a bell-crank lever pivoted on the shuttle and normally restrained from rotating about its pivot by an extension of the detector member, and adapted on freeing of the detector member to rotate so as to propel an arm of the lever through a warp sheet to bring about the operation of means disposed at the other side of the warp sheet for bringing weaving to an end.

5. In a circular loom a shuttle, a spool in said shuttle for supplying weft to be laid at the fell of the fabric, thread tensioning means disposed on the shuttle in the path of the thread at a point removed from the fell of the fabric, a pivoted detector member carried by the shuttle, a spring adapted to urge said detector member to rotate about its pivot, the detector member being restrained from moving by the tensioned thread

70 removed from the fell of the fabric, a pivoted detector member carried by the shuttle, a spring adapted to urge said detector member to rotate about its pivot, the detector member being restrained from moving by the tensioned thread

extending between the tensioning means and the fell of the fabric and freed for movement on thread breakage, a bell-crank lever pivoted on the shuttle, an extension formed on the detector member and adapted to contact with said bell-crank lever so as to restrain said lever against movement during normal weaving in the loom and to be moved out of contact with the lever by movement of the detector member on thread breakage, and a spring in association with said lever and adapted to rotate said lever about its pivot on removal of restraint from the lever so as to propel an arm of the lever through a warp sheet to bring about the operation of means disposed at the other side of the warp sheet for bringing weaving to an end.

6. In a circular loom, a shuttle for laying weft thread at the fell of the fabric, thread-tensioning means disposed in the path of the thread at a point removed from the fell of the fabric, a movable detector member carried by the shuttle and adapted to be restrained from movement by the tensioned thread extending between the tension-

ing means and the fell of the fabric and to be freed for movement on thread breakage, a pivot on the shuttle, two arms rotatable about said pivot, a spring connecting said arms and adapted to hold said arms in opened relation in the form of a bell-crank lever, an extension formed on said detector member and adapted to contact with one of said arms so as to restrain said arms against movement during normal weaving in the loom and to be moved out of contact with said arm by movement of the detector member on thread breakage, a further spring in association with said arms and adapted to rotate said arms about the pivot on removal of restraint from said arms so as to propel one of said arms through a relatively moving sheet of warp threads, said propelled arm being adapted to be rotated about the pivot relatively to the other arm by the warp threads so as to bring about the operation of means disposed at the other side of the warp sheet for bringing weaving to an end.
